Primary Examiner — Elizabeth J Oswecki*Assistant Examiner* — Yelizaveta Y Masalimova(74) *Attorney, Agent, or Firm* — Perkins Coie LLP(57) **CLAIM**

The ornamental design for a shoe, as shown and described.

DESCRIPTION

FIG. 1 is a perspective view of a shoe showing our new design;

FIG. 2 is a right-side view thereof;

FIG. 3 is a left-side view thereof;

FIG. 4 is a front view thereof;

FIG. 5 is a rear view thereof; and,

FIG. 6 is a top view thereof.

The broken lines in the drawings represent portions of the shoe that form no part of the claim.
